ATTORNEYS.

UNITED STATES PATENT OFFICE.

CHARLES O. BOSWORTH, OF SAN DIEGO, CALIFORNIA.

MEANS AND METHOD OF PREPARING ARTIFICIAL SNOW.

Application filed June 16, 1921. Serial No. 478,073.

To all whom it may concern:

Be it known that I, CHARLES O. BOSWORTH, a citizen of the United States, residing at San Diego, in the county of San Diego and 5 State of California, have invented a certain new and useful Means and Method of Preparing Artificial Snow, of which the following is a specification.

My invention relates to a means and method of preparing artificial snow and the objects of my invention are; first, to provide a new and novel process of preparing artificial snow; second, to provide a new and novel apparatus to be used in the preparation and 15 sale of artificial snow; third, to provide an apparatus of this class which combines a device for shaving the ice into the form of snow and displaying it in the form of falling snow; fourth to provide an apparatus of this 20 class which preserves the snow and reduces its liability to melt to a minimum and fifth, to provide an apparatus of this class which is simple and economical of construction, durable, easy to operate and which will not 25 readily deteriorate or get out of order.

With these and other objects in view as will appear hereinafter my invention consists of the novel process and certain novel construction, combination and arrangement 30 of parts and portions for carrying out my process as will be hereinafter described in detail and particularly set forth in the appended claims, reference being had to the accompanying drawings and to the characters of reference thereon which form a 35 part of this application, in which:

Figure 1 is a sectional view of my apparatus showing some of the parts in elevation to facilitate the illustration. Fig. 2 is a 40 front elevational view at a right angle to that of Fig. 1, Fig. 3 is a sectional view through 3-3 of Fig. 1 and Fig. 4 is a perspective view of the scattering member and Fig. 5 is an enlarged sectional view of the 45 knife support with the knife 8^a.

Similar characters of reference refer to similar parts and portions throughout the several views of the drawings.

The casing 1, main horizontal partition 2, 50 vertical partition 3, casing partition 4, door 5, compartment casing 6, scattering member 7, supporting platform knife 8, ice support-

ing frame 9, shaft 10, sheave 11, sheaves 12 and 13 and belt 14 constitute the principal parts and portions of my apparatus for preparing and displaying artificial snow. The casing 1 is preferably box-shaped and the walls thereof are hollow and filled with saw dust for providing insulation. It is provided with a main longitudinal partition some 55 distance from the upper side which is provided with an opening 2^a therein and with a vertical partition 3 extending downwardly from the partition 2 and forming a snow display compartment A, on the bottom of 60 which is provided a plurality of small cases 6 which are provided with openings adapted to receive the snow therein and extending from the partition 3 downwardly is the inclined member 3^a which is adapted to conduct the falling snow into the hole 6^a. These snow compartments are each provided with a door 6^b adapted to provide access from the outside to the snow. In the casing above 65 these doors 6^b is a glass 1^a. It is desired to 70 provide a double glass here to provide insulation and prevent the rapid melting of the snow which is displayed in falling form through this glass 1^a so that the public may 75 see it in the form of falling snow. Mounted 80 above the hole 2^a in the partition 2 is a scattering device consisting of a frame 7^c and parallel wire strands 7 and it is supported at each side on the upper edge of the partition 2 over the hole 2^a and it is reciprocated by means of a crank 7^a which is 85 revolvably mounted in bearings 7^b and on the upper end of the crank shaft 7^a is a sheave 13 upon which is mounted a belt 14 which extends over another sheave 12 secured to the 90 shaft 10. Mounted over this scattering member 7 is a supporting platform provided with knives 8^a and 8^b with their cutting edge extending at an angle and mounted directly over these knives is the frame 9 95 which is of the proper size to support a certain sized cake of ice which is placed within through a door 9^a on one side and the ice is taken in the receptacle through the door 5 on one side. This frame 9 is revolvably 100 mounted in the upper portion of the casing 1 by being secured to the shaft 10 and this shaft 10 extends up through the upper wall of the casing 1 and secured on the upper

end is a sheave 11 which is adapted for a belt from any driving mechanism. This shaft 10 is supported by means of bearings 10^a on opposite sides of the upper wall of the 5 casing 1 and it will be noted that the cake of ice is positioned in the frame 9 so that its lower edge rests upon the platform and is revolved by means of the shaft 10 which also revolves the shaft 7^a for reciprocating 10 the scattering device 7. The process consists of revolving the ice over knives for shaving the lower side of the cake of ice, then scattering the shaved ice in the form of snow so that it sprinkles downwardly through the 15 display compartment into the box compartment where it is taken and used for edible or other purposes as desired.

Though I have shown a particular process and a certain means and apparatus for 20 carrying out my process for preparing artificial snow I do not wish to be limited to this particular process nor to the construction as disclosed, but desire to include in the scope of my invention the process and construction, combination and arrangement substantially as set forth in the appended 25 claims.

It is obvious that there is provided a novel 30 process for preparing and displaying artificial snow; that there is provided novel means of preparing and displaying said snow; that the snow will be artificially provided by shaving the same by the revolution of the frame 9, carrying with it the 35 cake of ice over the knives 8^a and 8^b and that the shaved particles will be scattered so that they fall from the scattering device through the display compartment in the 40 form of falling snow; that the snow will be directed into the compartment 6 where it can be taken and fruit or flavoring added for use.

Having thus described my invention what I claim as new and desire to secure by Letters Patent is:

1. The herein described method of preparing and displaying artificial snow consisting in shaving the surface of a cake of ice, then scattering and displaying the 50 shaved portions in the form of falling flake snow.

2. The herein described method of preparing and displaying artificial snow consisting in shaving the surface of a cake of ice, then scattering and displaying the shaved portions in the form of falling flake snow, then storing the snow in close compartments.

3. An apparatus for preparing and displaying artificial snow, including a casing, an ice supporting frame revolvably mounted in said casing, a pair of knives with their cutting edges at an angle upon which the lower side of the cake of ice rests, means 60 positioned below said knives for scattering

the shaved ice in the form of snow and a display compartment positioned below said cake of ice.

4. An apparatus for preparing and displaying artificial snow, including a casing, 70 an ice supporting frame revolvably mounted in said casing, a platform with knives with their cutting edges extending upwardly on an angle therethrough upon which the lower side of the cake of ice rests, a display compartment positioned below said cake of ice and means for storing the ice shaved from said cake after it has passed through said compartment.

5. An apparatus of the class described, including a casing, a display compartment provided with a transparent side in said casing, a cake of ice supporting device revolvably mounted over an opening in the upper side of said display compartment, a platform upon which said cake of ice rests, a plurality of knives with their cutting edge at an angle positioned in said platform so that the cake of ice in said frame engages said knives and a scattering device reciprocably mounted between said knives and said display compartment.

6. An apparatus of the class described, including a casing, a display compartment provided with a transparent side in said casing, a cake of ice supporting device revolvably mounted over an opening in the upper side of said display compartment, a plurality of knives with their cutting edge at an angle positioned so that the cake of ice 100 in said frame engages said knives; a scattering device reciprocably mounted between said knives and said display compartment and means for revolving said cake of ice and frame support and for reciprocating 105 said scattering device.

7. An apparatus of the class described, including an insulated casing, a display compartment provided with transparent sides mounted in said casing, a plurality of snow receiving compartments in the lower side of said display compartment adapted to receive the snow passing through said display compartment, doors communicating with the interior of said compartment and extending to the outside of said casing, a scattering device forming a portion of the upper wall of said display compartment and reciprocably mounted therein, a plurality of knives positioned above said scattering device, a cake of ice supporting frame revolvably mounted above said knives adapted to revolve a cake of ice on said knives.

8. An apparatus of the class described, including an insulated casing, a display compartment provided with transparent sides mounted in said casing, a plurality of snow receiving compartments in the lower side of said display compartment adapted to receive the snow passing through said 120 compartment.

play compartment, doors communicating with the interior of said compartment and extending to the outside of said casing, a scattering device forming a portion of the upper wall of said display compartment and reciprocably mounted therein, a plurality of knives positioned above said scattering device, a cake of ice supporting frame rev-

olubly mounted above said knives adapted to revolve a cake of ice on said knives, and 10 means for revolving said frame.

In testimony whereof, I have hereunto set my hand at San Diego, California, this 10th day of June, 1921.

CHARLES O. BOSWORTH.
